UNITED STATES PATENT OFFICE.

AUGUSTE NAMUR, OF NEW YORK, N. Y., ASSIGNOR TO THE TUTTLE & BAILEY MANUFACTURING COMPANY, OF SAME PLACE.

DESIGN FOR A HOT-AIR-REGISTER FRONT.

SPECIFICATION forming part of Design No. 16,057, dated April 21, 1885.

Application filed February 16, 1885. Term of patent 14 years.

To all whom it may concern:

Be it known that I, AUGUSTE NAMUR, a citizen of Luxemburg, residing at New York city, in the county and State of New York, have invented and produced a new and original Design for a Hot-Air-Register Front, of which the following is a specification.

The accompanying print is a front or top view of my newly-invented design, in which the open fret-work front consists of the center ring, *a*, having the inner angular bar, *b*, and outer radial bars, *c*, said radial bars joining with squares *d*, arranged in a circle, joined at one angle to said radial bars *c*, joined together at other angles, and at their outer angle joined to rings *e* of the inner margin of the rim *j*, and said squares have a flower device, *f*, located in the center of each, and they are also connected to the center ring, *a*, by plain bars *h*, and also to the frame by curved bars *i*, which join said frame by rings *e*, intermediate to those by which the squares are connected to said rim. The border-frame *j* is ornamented with the

rings *e*, bars *l* and *m*, and the bows *n*, and flower figures *o* on the surface. 25

I claim—

1. In a design for a hot-air-register front herein shown, the open fret-work front consisting of the center ring, *a*, angular bars *b*, radial bars *c*, radial squares *d*, and the flower figures *f*, inclosed in the squares, said squares being connected to radial bars *c*, also connected together, and also connected to the border-frame, as set forth. 30

2. In a design for a hot-air-register front herein shown, the border-frame having the inner rings, *e*, bars *l* and *m*, bows *n*, and flower figures *o*, as set forth. 35

In witness whereof I have hereunto signed my name in the presence of two subscribing witnesses. 40

AUGUSTE NAMUR.
